LEG FOR AN IMPRINTING MACHINE OR THE LIKE

James G. McKay, Chicago, Ill.

Application January 19, 1959, Serial No. 54,217

Term of patent 14 years

(Cl. D33—14)

Fig. 1 is a perspective view of a leg for an imprinting machine or the like showing my new design;

Fig. 2 is a side elevational view of the same;

Fig. 3 is a bottom plan view of the same; and

Fig. 4 is a top plan view of the same.

The matter shown in broken lines is for illustrative purposes only. The rear surface of the leg is planar. I claim:

The ornamental design for a leg for an imprinting machine or the like as shown and described.
